Primary Examiner — Jack Reickel*Assistant Examiner* — Bobby W Jones, II(74) *Attorney, Agent, or Firm* — Birch, Stewart, Kolasch & Birch, LLP(57) **CLAIM**

We claim the ornamental design for a refrigerator filter, as shown and described.

DESCRIPTION

FIG. 1 is a perspective view of a refrigerator filter showing the new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is another perspective view showing a state of use thereof; and,

FIG. 9 is a cross-sectional view taken along the line 9-9 of FIG. 6.

The broken lines in the drawing figures are for the purpose of illustrating an environment of use and form no part of the claimed design.
